WORK-HOLDING AND POSITIONING MEANS

Edward Q. Kruchten, Chicago, Ill.

Application March 2, 1942, Serial No. 432,965

11 Claims. (Cl. 77—63)

My invention relates more particularly to work-holding and positioning means forming parts of a drill press to be used in connection with the operation of the press as for example for drilling, routing, carving and mortising and the producing of layouts and the spacing of work.

One of my more general objects is to speed up and simplify the various operations referred to.

Another object is to provide adjuncts to such machines as commonly provided, permitting the various operations to be performed on the work to be effected at greater speed and in a simpler manner than hitherto possible; and other objects as will be manifest from the following description.

Figure 1 is a view in front elevation of a drill press of common construction modified to embody my invention for use in the drilling, routing, etc., of work.

Figure 2 is a view in side elevation of the machine of Fig. 1.

Figure 3 is an enlarged plan view of the upper work-table of the press of Fig. 1, with my work-holding and positioning means thereon.

Figure 4 is a plan view of the upper work-table of the press stripped of work-holding and positioning means carried thereby.

Figure 5 is a view in front elevation of the structure shown in Fig. 5.

Figure 6 is a section taken at the line 6 on Fig. 3 and viewed in the direction of the arrow.

Figure 7 is a section taken at the line 7 on Fig. 3 and viewed in the direction of the arrow.

Figure 8 is a view like Fig. 3 of the upper work-table of the press showing it equipped with work-holding and positioning means embodying my invention, for use when it is desired the work be shifted along a predetermined arcuate path.

Figure 9 is a section taken at the line 9 on Fig. 8 and viewed in the direction of the arrow.

Figure 10 is an enlarged section taken at the line 10 on Fig. 8 and viewed in the direction of the arrow.

Figure 11 is a plan view of a piece of work to be operated on as for example to be drilled to form a circular series of holes in the work, illustrating the positioning of the work relative to the drill of the press for drilling the first hole of the series thereof.

Figure 12 is a plan view of the work of Fig. 11 showing the series of holes drilled therein.

Figure 13 is a plan view of the lower work-table of the press showing, by dotted lines, the work-holding and positioning means of Figs. 1-7, and 8-10, applied thereto.

Figure 14 is a view in side elevation of one of the similar clamping bolts forming parts of the structure on Fig. 13; and

Figure 15, an end view of the bolt of Fig. 14.

I have illustrated my invention as incorporated in a drill press of a well known construction and therefore a general description of the press will suffice.

It comprises a base 20 affording a lower horizontal work-table 21; a column 22 rising from the base 20; an upper work-table 23 mounted on the column 22 and adjustable up and down and rotatable thereon, being held in adjusted position by a clamp 24; a head 25 rotatable about, and movable up and down on, the column 22; a quill 25a vertically adjustable in the head 25 and a motor 26 on the head 25. The quill 25a contains a spindle rotatable therein and carrying a tool-chuck 27, shown as clutching a drill 28 in place, the spindle being rotated through the medium of mechanism (not shown) driven from the motor 26 by a belt 29 engaging a pulley 30 on the armature shaft 31 of the motor 26.

In accordance with one construction of such commonly known drill press, the upper table 23 has four radial slots, 32, 33, 34 and 35 therein spaced substantially 90° apart and a central aperture 36; and the lower table 21 has two parallel slots 37 and 38 and a central aperture 21a (Fig. 13), these radial and parallel slots being provided for receiving the means commonly provided for clamping the work-holding vises to the tables, it being understood that only one work-table at a time is used.

Referring now more particularly to my invention as applied to the upper table 23, the holding and positioning means for the work to be operated on by the tool in the drill press and shown as a drill, comprises a plate 39 formed of the plate member 40 and a bar 41 rigid therewith, the plate member 40 of the plate 39 having a pair of parallel slots 42 and 43 which in the applied position of the plate 39 to the table 23 intersect the radial slots 32, 33, 34 and 35 in the table 23. The bar portion 41 of the plate 39 which is located between the points of intersection of the parallel and radial slots is formed with an undercut guide-way 44 in its upper surface extending lengthwise of the bar-portion 41 throughout the length of the latter.

The means now being described also comprise a pair of clamp-jaws 45 and 46 having base portions 47 and 48 at which they are slidable on the bar-portion 41, being held in independently adjusted position along the bar portion 41 by

clap bolts comprising flanged heads 49 slidable in the undercut groove 44 in the plate 39, threaded studs 50 rising from the heads 49 through the base portions 47 and 48 and clamp nuts 51 screwed on the upper threaded ends of the studs 50 and against the base portions 47 and 48, the base portion of the clamp 45 having a rib 52 which extends into the undercut groove 44 preventing the clamp 45 from rotating on the plate 39.

The inner edges of the base portions 47 and 48 of the clamps 45 and 46 are provided with vertical flanges 53 and 54, respectively, at which to clamp the work. The clamp 46 is free to swing about its clamp bolt 50 as a pivot and is provided at its inner face with a plate 55 normally yieldingly drawn toward this face by coil springs 56 surrounding pins 57 secured to the plate 55 and confined between heads 58 on these pins and the flange 54. The plate 55 is thus adapted to be adjusted against the work to be clamped by means of set screws 59 screwed in the flange 54 and bearing against the plate 55.

The plate 39 is provided on its upper surface with a lineal scale exposed to view between the clamp jaws 45 and 46 and reading in opposite directions from center line markings 60 which, if extended, would intersect the center of a threaded opening 61 in the center of the plate 39, the arrangement described permitting the clamps 45 and 46 to be adjusted to any of equal distances from the center opening 61.

The structure also comprises a pair of clamp bolts 62 and 63 which extend through the parallel slots 42 and 43 and diametrically opposed ones of the radial slots, as for example the slots 32 and 34 as shown in Fig. 3.

In the loosened condition of the clamp bolts 62 and 63 the plate 39, with the work clamped thereon, has universal movement on the table 23 in a horizontal plane throughout somewhat more than 90° and by reversing the positions of the clamp bolts 62 and 63, upon reaching the limit of rotatable adjustment of the plate 39 on the table 23 in the first installation of the clamp bolts, to position these bolts in the parallel slots 42 and 43 and in the others of the diametrically opposed radial slots—the slots 33 and 35 in the example above given—universal movement of the plate 39 on the table 23 in a horizontal plane throughout substantially an additional 90° may be effected. Further additional substantially 90° rotational movements are permitted by successively positioning the clamp-bolts 62 and 63 in the first and second above referred to positions, respectively.

The operator may thus quickly adjust the work on the table 23 into accurate registration with the tool 18 in the press for operating on the work at the exact point desired, without removing the clamp-bolts, within the range of each 90° movement, the work having been preliminarily provided with a center punch mark to indicate the point at which the tool is to engage the work. Following the positioning of the work as described the operator tightens the clamp-bolts 62 and 63 to hold the work firmly in position and the quill 25a, and with it the chuck and tool 28, is lowered to engage the tool with the work.

The assembly of the work-holding plate 39 and clamps 45 and 46 with the lower table 21 and with two clamp bolts herein represented at 64 and 65 positioned in the slots 42 and 43 in the plate 39 and in the slots 37 and 38 in the table 21, all as shown by dotted lines in Figs. 1, 2 and 13, also

permits of the universal movement of the plate 39 on the table 21 in a horizontal plane.

In the positioning of the clamp bolts 64 and 65 as shown by dotted lines in Figs. 1, 2 and 13 the work holding and positioning means may have universal movement throughout substantially 180° and to permit of such movement throughout the remaining 180° the clamp bolts 64 and 65, which in this operation have moved to the opposite ends of the slots in which they were originally located, would be removed from these slots, and the clamp bolt 64 repositioned in the longitudinal slot 43 at the end thereof opposite that in which it was originally positioned and positioned in the radial slot 38 in the position originally occupied by the clamp bolt 65.

The clamp-bolts 64 and 65 are shown of a special form to permit them to be tightened and loosened at their upper ends rather than at their lower ends which would require applying the wrench to the underside of the table 21 which is commonly rather difficult because of the design of the press. To this end the heads 66 of the clamp bolts 64 and 65 which would be positioned at the underside of the table 21 are preferably elongated, as shown, permitting them to be passed downwardly through the longitudinal and radial slots referred to and upon partial rotation lap the undersurface of the table 21, the nuts 67 of the clamp bolts being screwed upon the upper ends of the shanks of these bolts.

Referring now to the construction shown in Figs. 8, 9 and 10 for drilling, by way of example, a circular series of holes in the work as shown in Fig. 12, and supported on the upper table 23; this construction is identical with that shown in Figs. 1-7, inclusive, except for the addition of a protractor disk 71 interposed between the plate 39 and the table 23 and means connecting together this plate and disk for rotatable adjustment, as a unit, on the table 23 about the axis of the opening 61.

The means just referred to are shown as comprising a clamp-screw 72 which extends through the opening 36 in the table 23 and a central opening 73 in the disk 71 and screws into the threaded central opening 61 in the plate 39, and a washer 74 at the underside of the disk 71 and surrounding the screw 72 above its head 75 and rotatable in the opening 36 in the table 23, the disk 71 and washer 74 being clamped between the plate 39 and the screw-head 75 upon tightening the screw 72. To ensure against rotational relative displacement of the plate 39 and disk 71, the disk 71 is formed with struck-up projections 76 at equally spaced intervals therein in a circular series about the center of the disk 71 for registration with sockets 77 similarly spaced in a circular series in the underface of the plate 39.

The protractor disk 71 has parallel slots 78 and 79 therein which register with the parallel slots 42 and 43, respectively, in the plate 39 to receive the clamp bolts 62 and 63 provided to clamp the plate 39 to the table 23 in the various positions of adjustment of the plate 39, which in the case of this particular assembly are rotational only about the axis of the clamp screw 72.

The peripheral portion of the disk 71 extends radially outwardly beyond the marginal edges of the plate 39 and bears a circular protractor scale

on its upper surface, graduated to represent degrees, each quarter segment thereof being graduated from 0° to 90° as shown, the upper surfaces of the projecting corners of the table 23 having indexing marks 80, 81, 82 and 83 spaced apart 90° for cooperation with the protractor scale.

In the use of this arrangement for drilling the work, represented at 84 in Figs. 11 and 12 as a square block to be drilled for producing equidistantly spaced holes 85 arranged in a circular series in a predetermined position in the work, the clamps 45 and 46 would be set to extend at equal distances from the center markings 60 of the scale on the plate 39. The work holding and positioning means and table 23 would then be rotatably adjusted as a unit about the column 22 to line up with the tool 28, the center 86 about which the circular series of holes 85 to be drilled, is described, as shown by the full line positioning of the drill 28 in Fig. 11. The table 23 would then be rotatably adjusted about the column 22, and the work-holding and positioning means about their central pivot 12, to vertically aline a punch mark 87 on the work with the drill 28 shown by dotted lines so alined (Fig. 11), the punch-mark 87 having previously been made in the work to indicate the location of the circumference of the circle to be described by the circular series of holes (the radius of the circle being measured from the center of said circular series of holes to the center of the holes of said series) and to indicate the exact location of the first hole to be drilled. The clamp bolts 62 and 63 are then tightened and the first hole drilled.

The operator, in such positioning of the parts for drilling the first of the holes 85, notes the degree marking on the scale of the protractor disk 71 which registers with the indexing marks 80-83 (the reading being the same at each of these marks) and for the drilling of the second of the holes 85 of the series first loosens the clamp bolts 62 and 63 and then rotates the unitary work holding and positioning means and protractor disk 71 the number of degrees corresponding with the center to center spacing of the adjacent ones of the desired holes 85, maintaining the table 23 in its position of rotational adjustment about the column 22 in alining the drill 18 with the punch-mark 87; it being understood that the operator has previously computed the number of degrees of the desired spacing of the holes 85. He then tightens the clamp bolts 62 and 63 and proceeds to drill such second hole. The cycle of operations above described is repeated for the drilling of the remaining ones of the holes 85 of the series to be drilled.

As will be understood, the construction just described may be used to produce merely a "lay out" arcuate arrangement when such is desired, as distinguished from drilling holes in an arcuate arrangement.

The protractor feature may also be used with the lower table 21 as shown by dotted lines in Fig. 13. In this case the washer 14 would be entered in the opening 21a in the table 21 and the alining of the work at its punch-mark 87 with the drill 28 is accomplished by rotating the head 25 about the column and slidably adjusting the work in the clamps 45 and 46 to the proper position. The head 25 is then rotated on the column 22 and the work holding and positioning means rotated about their central pivot 12 at the opening 21a, to aline the drill 28 with the punch-mark 87.

In this case the clamp bolts 62 and 63 after intermittent rotations of the work holding and po-

sitioning means and the protractor disk 71 throughout 180° , would be repositioned in the slots in the table 21 and plate 39 for permitting rotation of these means and disk on the table 21 throughout the remaining 180° to complete full rotation of these parts as explained above in connection with these means where the protractor disk 71 is omitted.

It will be understood that in case the protractor feature is not to be availed of for the determining of the spacing of the holes in an arcuate arrangement, in which case the work would be punch-marked for the location of each hole, nevertheless the feature of providing a pivoting means for the unit comprising the plate 39 and the work-clamping features may be used to advantage.

While I have illustrated certain particular constructions constituting embodiments of my invention, I do not wish to be understood as intending to limit my invention thereto as the same may be variously modified and altered and the invention embodied in other forms of structure without departing from the spirit of my invention.

What I claim as new, and desire to secure by Letters Patent, is:

1. Work-holding and positioning means for use with work tables having either parallel or radial slots, comprising: a plate having a plurality of spaced apart slots, portions of said slots registering with slots in a table when centered thereon in different positions of rotation, means to releasably secure said plate to said table in adjusted positions, said means positioned in registering portions of the slots in the table and plate, a circular plate underlying said first named plate and formed with slots registering with the slots of the first named plate, means to preserve registry of said plate, and means to pivot the registering plates upon the table.

2. The combination of a work table, work-holding and positioning means comprising a plate pivoted on said table, both said table and plate having slots spaced apart, portions of said slots in said table and plate intersecting in different positions of rotational adjustment of said plate, means for indicating the degree of rotatable adjustment of said plate, comprising a protractor disk formed separate from said plate and disposed between said plate and table and rotatable with said plate, and means for releasably securing said plate to said table in rotatably adjusted position thereon positioned in certain of the slot intersections.

3. The combination of a work table, work-holding and positioning means comprising a plate on said table, said table and plate having slots, portions of said slots registering in different positions of universal adjustment of said plate on said table, means for releasably securing said plate to said table in adjusted positions thereon positioned in the registering portions of said slots, a circular protractor plate underlying said first-named plate and similarly slotted with its slots registering with the slots in said first-named plate and pivot means to center said combined plates with a table.

4. Work-holding and positioning means for use with work tables having either radial or parallel slots, comprising: a plate formed with slots spaced apart; removable means to pivot said plate on a table of either of said types; portions of said plate slots intersecting in different positions of rotational adjustment on the table with different

portions of the table slots with the pivoting means in place and in different positions of universal adjustment of the plate on the table with the pivoting means removed; means for indicating the degree of rotational adjustment of the plate on the table; means for releasably securing said plate to a table of either of said types in adjusted position thereon positioned in certain of the slot intersections and when loosened permitting adjustment of the plate on the table; and means carried by said plate to hold work in position thereon, comprising a pair of vise jaws each adjustable in a rectilinear path on said plate to any position thereon in said rectilinear path.

5. Work-holding and positioning means for use with work tables having either radial or parallel slots, comprising: a plate formed with slots spaced apart; removable means to pivot said plate on a table of either of said types comprising a protractor disk formed separate from said plate, slotted in conformity with the slots of said plate, disposed between said plate and table and rotatable with said plate; means to pivot said disk and plate jointly on a table of either of said types; means to indicate the position of rotational adjustment of the disk and plate on the table; means for releasably securing said plate on a table of either of said types in adjusted position thereon positioned in certain of the slot intersections and when loosened permitting adjustment of the plate and disk on the table; and work-holding means carried by said plate, formed to permit adjustment of any point of the work longitudinally of the plate in a rectilinear path.

6. Work-holding and positioning means for use with work tables having either parallel or radial slots, comprising: a plate of a size of the same order as that of the tables with which it is to be used, having at least two continuous generally parallel slots, each slot being at least as long as the shortest distance therebetween, portions of the slots of the table and plate registering in different positions of adjustment of the plate on the table; and at least two means for releasably securing said plate to the table in adjusted positions thereon, at least one securing means passing through each of two slots in the plate and through registering portions of slots in the table.

7. Work-holding and positioning means for use with work tables having either parallel or radial slots, comprising: a plate of a size of the same order as that of the tables with which it is to be used, having at least two continuous parallel slots of substantially the same length spaced the same distance as the slots in a parallel-slot table with which it is to be used, each slot being at least as long as the distance therebetween, portions of the slots of the table and plate registering in different positions of adjustment of the plate on the table; and at least two means for releasably securing said plate to the table in adjusted positions thereon, at least one securing means passing through each of two slots in the plate and through registering portions of slots in the table.

8. Work-holding and positioning means for use with work tables having either parallel or radial slots, comprising: a vise having a base portion and at least one movable jaw portion movable along a given line; a plate of a size of the same order as that of the tables with which it is to be used, having said vise rigidly mounted on the upper surface thereof, said plate having at least two continuous generally parallel slots

on opposite sides of said vise and generally parallel to said line of jaw movement, each slot being at least as long as the shortest distance therebetween, portions of the slots of the table and plate registering in different positions of adjustment of the plate on the table; and at least two means for releasably securing said plate to the table in adjusted positions thereon, at least one securing means passing through each of two slots in the plate and through registering portions of slots in the table.

9. Work-holding and positioning means for use with work tables having either parallel or radial slots, comprising: a vise having a base portion and at least one movable jaw portion movable along a given line; a plate of a size of the same order as that of the tables with which it is to be used, having said vise rigidly mounted on the upper surface thereof, said plate having at least two continuous parallel slots of substantially the same length spaced the same distance as the slots in a parallel-slot table with which it is to be used, each slot being at least as long as the distance therebetween, portions of the slots of the table and plate registering in different positions of adjustment of the plate on the table; and at least two means for releasably securing said plate to the table in adjusted positions thereon, at least one securing means passing through each of two slots in the plate and through registering portions of slots in the table.

10. Work-holding and positioning means for use with work tables having either parallel or radial slots, comprising: a vise having a base portion and at least one movable jaw portion movable along a given line and means operative to adjust the relative positions of the jaws; a plate of a size of the same order as that of the tables with which it is to be used, having said vise rigidly mounted on the upper surface thereof, said plate having at least two continuous generally parallel slots of substantially the same length on opposite sides of said vise and generally parallel to said line of jaw movement, each slot being at least as long as the shortest distance therebetween, portions of the slots of the table and plate registering in different positions of adjustment of the plate on the table; and at least two means for releasably securing said plate to the table in adjusted positions thereon, at least one securing means passing through each of two slots in the plate and through registering portions of slots in the table.

11. Work-holding and positioning means for use with work tables having either parallel or radial slots, comprising: a plate of a size of the same order as that of the tables with which it is to be used, having at least two continuous parallel slots of substantially the same length spaced the same distance as the slots in a parallel-slot table with which it is to be used and a greater distance than that between the adjacent ends of opposite slots in a radial-slot table with which it is to be used, each slot being at least as long as the distance therebetween, portions of the slots of the table and plate registering in different positions of adjustment of the plate on the table; and at least two means for releasably securing said plate to the table in adjusted positions thereon, at least one securing means passing through each of two slots in the plate and through registering portions of slots in the table.
